UNITED STATES PATENT OFFICE.

BERNARD T. MESKER, OF ST. LOUIS, MISSOURI, ASSIGNOR TO MESKER BROTHERS IRON COMPANY, OF ST. LOUIS, MISSOURI, A CORPORATION OF MISSOURI.

METAL CASKET.

1,421,018.

Specification of Letters Patent. Patented June 27, 1922.

Application filed October 9, 1919. Serial No. 329,485.

To all whom it may concern:

Be it known that I, BERNARD T. MESKER, a citizen of the United States, residing at St. Louis, Missouri, have invented a certain 5 new and useful Improvement in Metal Caskets, of which the following is a full, clear, and exact description, such as will enable others skilled in the art to which it appertains to make and use the same, reference 10 being had to the accompanying drawings, forming part of this specification.

My invention relates to new and useful improvements in metallic caskets or coffins and particularly to the type of caskets or 15 coffins that are pressed or drawn from sheet metal.

The principal objects of my invention are, to generally improve upon and simplify the construction of the existing types of sheet 20 metal caskets; to provide a construction which gives the casket body and its cover the requisite strength and rigidity; to provide an improved sealing joint between the body of the casket and the removable top 25 or cover thereof, such joint being effected through the direct contact of parts of said body and removable top or cover, thereby entirely eliminating the necessity for providing the bolts, band iron and gasket or 30 packing strips that are usually positioned between the contacting parts; to provide a construction wherein the bottom plate of the casket body is recessed so as to form a marginal bead or rib which can be readily 35 grasped by the hands while the casket is being lifted and moved from one point to another, and at the same time to materially increase the rigidity of the bottom portion 40 of the casket; and, further to provide a casket of graceful contour and of a neat and finished appearance.

With the foregoing and other objects in view, my invention consists in certain novel features of construction and arrangement of parts, hereinafter more fully described and claimed, and illustrated in the accompanying drawings, in which—

Figure 1 is a top plan view of a sheet metal casket constructed in accordance with 50 my invention.

Figure 2 is a cross sectional view taken approximately on the line 2—2 of Figure 1.

Figure 3 is a plan view of a casket hav-

ing the removable top or cover formed in two parts.

55

Figure 4 is an enlarged section taken approximately on the line 4—4 of Figure 3.

Figure 5 is an enlarged cross section taken approximately on the line 5—5 of Figure 3.

60

Figures 6 and 7 inclusive are detail sectional views of modified forms of sealing joints that are adaptable for use between the removable top or cover of the casket and the body thereof.

Figure 8 is a plan view of a further modified form of the casket.

65

Figure 9 is an enlarged cross section taken approximately on the line 10—10 of Figure 8.

Figure 10 is an enlarged cross section taken approximately on the line 11—11 of Figure 8.

70

Referring by numerals to the accompanying drawings and particularly to the form of casket illustrated in Figures 1 and 2, 10, 75 10 designate the side walls of the body of the casket, the same being pressed or drawn from sheet metal and their lower portions preferably extended upwardly to form reinforcing ribs or beads 11. The lower edges 80 of these rib or bead portions 11 are extended horizontally inward as designated by 12 and secured thereto in any suitable manner are the edges of the casket bottom 13, the latter being preferably formed from a single piece 85 of sheet metal. The main body portion of this bottom is elevated with respect to the edges that are secured to the beads or ribs 11 and by virtue of such construction, a recess 14 is provided, said recess being continuous along the sides and ends of the casket body, thus enabling the fingers of the 90 hands to grip the lower corners of the casket body while the same is being lifted and carried from one point to another. If desired, 95 one or more strips of wood or analogous material may be applied to the underside of the bottom 13, as illustrated by dotted lines in Figure 2, such strips serving as bearings for the rollers located in the bed or bottom 100 of a hearse, and adding rigidity to the lower portion of the casket.

It will be understood that the end walls of the body of the casket are formed integral with the side walls 10 and said end walls 105 may be of any desired shape, either rounded,

angular, square, or elliptical. The upper portions of the side and end walls of the casket body are provided with outwardly projecting upper finishing beads 15 which, 5 in addition to materially strengthening the upper portion of said body, lend to the casket a neat and finished appearance. The upper portions of these beads 15 are formed with inverted U-shaped beads 16, the legs of 10 which are spaced a substantial distance apart and arranged parallel with each other, thereby forming a strengthening member which combines with the upper finishing bead 15 to give the upper portion of the casket body 15 strength and rigidity, and, in addition, said inverted U-shaped bead forming the seat for the marginal portion of the casket closure.

The inner vertical leg 16a of the inverted 20 U-shaped bead 16 is extended downwardly a short distance below the plane occupied by the lower end of the outer leg and the lower portion of this inner leg terminates in a U-shaped bead or strengthening rib 17.

25 The closure for the casket body thus formed is pressed from a single piece of sheet metal and the main body portion of said closure is convexed upwardly as designated by 18 so as to provide a graceful contour 30 and the marginal edge of said closure terminates in a continuous inverted U-shaped bead 19 of such size as to fit snugly upon the inverted U-shaped bead 16 on the casket body.

35 Thus when the closure is applied to the casket body, all parts of the inner surface of the inverted U-shaped rib or bead 19 are in direct contact with the outer surfaces of the inverted U-shaped rib or bead 16, thus forming 40 a sealing joint between the closure and the body that is air and water-tight, such joint being produced without the use of any extraneous means such as gaskets or packing strips.

45 If desired, an inner closure such as a sheet metal plate 20 may be provided, the edges of the latter terminating in depending flanges 21 which, when the inner closure is applied for use, occupy the grooves in the U-shaped 50 beads 17.

In Figures 3, 4 and 5 I have illustrated a form of casket wherein the closure is made in two parts and there being a glazed panel arranged beneath the shorter one of the parts 55 of the top closure, said panel carrying a section of glass or transparent material, this construction being designed for the purpose of giving view to the head and upper portion of the body of the corpse occupying the casket. In this construction 22 and 23 60 designate respectively, the long and short sections of the closure, the side and outer end portions of which terminate in inverted U-shaped ribs 24 which are adapted to fit 65 snugly over the corresponding inverted U-

shaped portions of the casket body and the inner end of the longer section 22 is extended vertically downward as designated by 25 and the lower portion of this downward extension terminating in a U-shaped rib 26. 70 The inner end of the shorter section 23 terminates in a depending portion 27 which fits snugly against the adjacent face of the depending portion 25 and the lower edge of said depending portion 27 being adapted to 75 occupy the U-shaped rib 26 when the parts of the closure are properly assembled. (See Fig. 4).

A substantially rectangular frame 28, 80 preferably formed of sheet metal, is normally disposed directly beneath the short section 23 of the closure, said frame carrying a section 29 of glass, silk gauze or like transparent material, and the sides of said frame being provided with depending 85 flanges 30 which occupy and are arranged to slide in the U-shaped portions 17 that are formed on the inner legs of the inverted U-shaped beads 16.

The construction just described, provides a 90 relatively simple and effective air and water-tight sealing joint between the body of the casket and the closure therefor and at the same time provides a construction wherein a portion of the closure can be readily removed to permit the head and upper portion of the body of the corpse to be conveniently viewed through the section of glass or transparent material 29.

In Figures 6 and 7, I have illustrated 100 modifications of the sealing joint between the body of the casket and the closure therefor, which can be easily and cheaply produced and which are effective in forming air and water-tight joints.

In the construction illustrated in Figure 6, a portion of the upper finishing bead 15 is bent into a substantially vertical plane to form a leg 30 and the material adjacent to this leg is bent to form a U-shaped bead 110 or rib 31. The marginal edge of the closure that is designed to be used on this form of casket terminates in a U-shaped portion 32 which is adapted to fit snugly within the U-shaped rib or bead 31, and the outer leg 115 of said U-shaped portion 32 is provided with a horizontally disposed flange 33 which extends slightly beyond the vertical leg 30, thereby forming a projection which may be engaged by a suitable tool when it is desired to remove the closure from the casket body.

In Figure 7 I have shown means for effectively retaining the closure upon the casket body, such means comprising a slight 125 projection 44 that is pressed outwardly from the outer leg of the inverted U-shaped portion 16 on the casket body and said projection being adapted to engage in a seat 45 that is formed in the outer leg of the in- 130

verted U-shaped portion 19 of the closure and which seat is formed by pressing a portion of the metal of said outer leg outwardly. This retaining means is effective in 5 firmly securing the closure to the casket body while these parts are temporarily assembled or while the empty caskets are being shipped from one point to another.

In Figure 8 I have shown a casket provided with a sealing member which includes a closure plate 46 preferably formed of sheet metal and provided along its marginal edge with an inverted U-shaped member 47 that is adapted to fit snugly over and 10 make sealing contact with the inverted U-shaped bead or member 16 on the upper portions of the side and end walls of the casket body.

If desired, one end of this closure member 46 may be formed with a frame in which is located a section 48 of glass or transparent material. Where this construction is carried out, the metal of the member 46 adjacent to one end thereof and the 20 metal at the sides of said member adjacent to said end are extended inwardly and upwardly a short distance as designated by 49, and then said metal is bent to form inverted U-shaped ribs 50. From the inner ends of these legs the metal is extended inwardly and thence rearwardly to form substantially horizontal flanges 51, and immediately below said flanges the metal is bent downwardly, thence inwardly to form 30 channel portions 52 which receive the corresponding edges of the transparent member 48. This frame for the transparent member is completed by a transversely disposed rail 53, the lower portion of which is formed on 35 a channel 54 adapted to receive the corresponding edge of the transparent member 48. A cover 56 for this transparent portion of the closure is formed of sheet metal and the sides and outer end of this cover are 40 formed into depending legs or flanges 58 which, when the cover is applied for use, rest directly upon the flanges 51 and fit snugly against the inverted U-shaped ribs 50. (See Figs. 9 and 10.) This cover is 45 formed so that its main body portion lies flush or in the same plane with the main body portion of the sealing cover 46. If desired, an outer cover 57 may be provided, said outer cover being formed of sheet 50 metal and provided at its edges with depending flanges 58 which, when the cover is applied for use, rest directly upon the body of sealing cover 46 and bear against the inner legs of the inverted U-shaped portions 55 60 67 thereon. (See Fig. 10.)

In some instances it may be found desirable to provide a sealing closure with a section of plate glass or the like which extends practically the entire length of the 65 casket and where this construction is car-

ried out, the transverse rail 53 is dispensed with and the channel portion 52 of the frame of the closure extends the entire length and width of said frame, and thus accommodating a single full length section 70 of glass, as illustrated by dotted lines in Figure 9.

A casket of my improved construction may be produced at very low cost inasmuch as it is composed of but relatively few parts 75 and which latter may be pressed or drawn into proper shape by suitable dies; further, the casket has great strength and rigidity due to the formation of the upper and lower beads on the body and also by reason of the 80 formation of the marginal bead on the closure and the cooperation of said closure and bead with the upper marginal bead on the casket body. The interengaging beads on the casket body and the closure in 85 addition to adding strength and rigidity to the completed structure are effective in producing without the use of extraneous means a sealing joint that is air and water-tight, the same being simple and inexpensive of 90 manufacture, and being particularly effective by virtue of the fact that a considerable portion of the metal of the closure makes direct contact with a considerable portion of the metal on the casket body. 95]

It will be readily understood that minor changes in the size, form and construction of the various parts of my improved casket can be made and substituted for those herein shown and described, without departing 100 from the spirit of my invention, the scope of which is set forth in the appended claims.

I claim:

1. In a casket, a side wall reinforced along its upper edge by bending the same 105 to form a rib, an integral convex closure seat formed above said rib, an outer closure having a concave perimetric flange for engaging said seat in sealing contact, the inner edge of said seat being refolded inwardly and upwardly to form a supporting trough for an inner closure. 110

2. In a casket, a body side wall terminating in a U-shaped flange of sheet metal, a removable cover, the edge of which terminates in a U-shaped flange of sheet metal, 115 said U-shaped flanges having contact with each other extending a substantial distance transversely of the flanges, whereby they cooperate to form a self-sealing joint between said cover and body side wall. 120

3. In a casket, a side wall pressed from a single sheet of metal, an integral inverted U-shaped flange at the upper edge of said wall projecting inwardly therefrom, a U- 125 shaped terminal on said flange, said flange and terminal being adapted respectively to be received in and to receive correspondingly shaped cover members to form sealed joints therewith. 130

4. In a casket, a side wall pressed from a single sheet of metal, an integral U-shaped flange at the upper edge of said wall projecting inwardly therefrom and facing downwardly, a U-shaped terminal on said flange projecting inwardly therefrom and facing upwardly, an outer closure, a U-shaped bend on the edge of said closure adapted to fit said flange, an inner closure, and a downwardly projecting rib on said inner closure adapted to be seated in said terminal.
5. In testimony whereof I hereunto affix my signature this 6th day of October, 1919.

BERNARD T. MESKER.
